UNITED STATES PATENT OFFICE.

GEORGE COLE, OF LONDON, COUNTY OF MIDDLESEX, ENGLAND.

MECHANISM FOR TRANSMITTING MOTION TO TOY FIGURES AND OBJECTS.

SPECIFICATION forming part of Letters Patent No. 423,905, dated March 25, 1890.

Application filed July 23, 1888. Serial No. 280,788. (No model.) Patented in England June 2, 1886, No. 7,400.

To all whom it may concern:

Be it known that I, GEORGE COLE, of the firm of George Cole & Co., merchants and manufacturers, of 13 and 15 Finsbury Street, 5 London, in the county of Middlesex, England, a subject of the Queen of Great Britain, have invented certain new and Improved Mechanism for Transmitting Motion to Toy Figures and Objects, (for which I have received Letters Patent in Great Britain, No. 7,400, dated the 2d day of June, 1886,) of which the following is a specification.

This invention relates to improvements in the arrangement and application of mechanism for actuating toy figures, effigies, or animals represented as in the act of boxing, wrestling, running, and the like, or other mechanical operation.

In order that my invention may be clearly understood and readily carried into practice, I will proceed to describe the same with reference to the accompanying drawings, which show two examples of the manner in which my improved mechanism is arranged and constructed in accordance with my present invention and applied so as to actuate mechanical toy figures, in the cases shown in Figures 1, 2, and 3 these figures being represented in the act of boxing.

In the drawings, Fig. 1 shows the back elevation, and Fig. 2 the side elevation, of toy boxers actuated by a spring - motor. Fig. 3 shows another arrangement in which the motor is a free rotating top spun in a cup or bearing. Fig. 4 shows another plan for obtaining motion from a free rotating top, as hereinafter explained. Fig. 5 shows a side elevation, and Fig. 6 a plan, of the train of wheels forming the clock-work motor *f*, suitable for the purposes hereinafter described. Fig. 7 is a side view, and Fig. 8 a plan, of the top plate or frictional disk *e* of the top or motor, showing the projections or cross-bars *x* thereon, which may be of greater or less number, as desired.

b is a frame-work standing on legs *b'*. A cranked axle or shaft *a*, with crank *a''*, (hung in a hole or groove,) passes through the frame-work *b*. The end of the axle or shaft *a*, after 50 passing out at the bottom of the frame-work *b*, is bent to form a lever or crank arm *a'*.

From the end of lever *a'* is suspended or

hung by means of a flexible cord *c* a ball, (advantageously of india-rubber,) weight, or pendant *d* of any suitable shape. Underneath 55 the frame-work *b* (referring to Figs. 1 and 2) is placed a base-plate or stand *f*, which by means of an axle or shaft *e'* supports a frictional disk or table *e* (which may be of any suitable shape) in such a manner that it can 60 be made to revolve freely. The stand *f* is so placed that the ball, weight, or pendant *d*, or its cord *c*, is allowed to rest or partly rest upon the frictional disk or table *e* or come into contact with some part of the disk *e* which may 65 have projections or cross-plates upon it for the purpose of such contact. A figure *g* is suspended or loosely hung upon one end of a bent lever *i*, its fulcrum being kept at *i'*. On the other end of the bent lever *i* is formed a loop or 70 eyelet. Into this loop or eyelet one end of a connecting-rod *k* is hooked, the other end of the rod being bent loosely round the crank *a''* of shaft *a*. The figure *h* is connected in a similar manner to crank *a''* by means of a 75 bent lever *j* and connecting-rod *l*. The frictional disk or table *e* being made to revolve by clock-work, (in Fig. 6 is shown a spring-barrel *s* and train of wheels for revolving the axis *e'* at a high rate of speed, the table *e* being attached to the axis *e'* and thereby revolved,) springs, or other suitable means, the ball or weight, coming into contact, is made to swing, jerk, and rotate violently, thereby causing intermittent and jerking motion, 80 which by means of the lever *a'*, crank *a''*, connecting-rods *l* and *k*, and bent levers *j* and *i* is transmitted to the figures *g* and *h*, causing them to appear as in the act of boxing.

In Fig. 3 the parts *e*, *e'*, and *f*, Figs. 1 and 2, 90 are replaced by a free rotating top *m*, which is spun in the cup *o*, provided for that purpose, to keep the said top in its proper position while spinning, the upper part or frictional disk *n* of the spinning top having the 95 same action on the suspended ball, weight, or pendant *d* as the frictional disk or table *e*, Figs. 1 and 2, before described, to which similar additions may be made. The cup *o* is advantageously made of china and mounted in 100 the base of the frame of the toy, as shown, or in any suitable manner. A variety of other toy figures, animals, or objects may be worked in a similar manner, causing them to appear

as in the act of wrestling, dancing, running, or performing other various mechanical operations in accordance with my invention.

Fig. 4 shows another modification, the action 5 or motion of a free rotating top *m* (spun in a cup or holder *o*) being utilized to actuate or swing in jerks the pendulum or arm *s* to and fro by means of the suspended ball, weight, or pendant *d* and cord *c* coming in contact with the frictional disk *n*, as before described, which thus causes the jerky partial rotation 15 of the axis *t*, which motion can be readily adapted for actuating toy figures, such as sawing, playing the fiddle, or such like movements. The above arrangement is also applicable to the disk *e*, described with reference to Figs. 1 and 2. It will thus be seen that by the arranging or mounting a ball, weight, or pendant—such as *d*—suspended on 20 a flexible cord or connection *c*, in juxtaposition and acting in conjunction with a free rotating top or other motor having a like revolving disk or surface, a jerky intermittent motion is obtained and can be transmitted to 25 actuate numerous mechanical toys.

I do not desire to claim herein separately either the motor or the free rotating top, which latter, in combination with other parts,

forms the subject-matter of another application by me for Letters Patent of the United States, Serial No. 280,787.

Having fully described my invention, what I desire to claim and secure by Letters Patent of the United States is—

1. In actuating toy figures and objects, the 35 combination of a weight *d*, suspended by means of a flexible cord *c* to a crank-arm *a'* on a crank-axle *a*, with a rotating frictional disk upon which the suspended weight *d* comes in contact, substantially as set forth. 40

2. In mechanism for actuating toy figures and objects, an upright crank-axle having a crank therein hung loosely at its upper end and having its lower end formed so as to serve as a crank-arm, to the end of which 45 latter is attached a weight or ball by means of a flexible cord, which suspended weight comes in contact with a frictional disk forming the top part of a spinning top or revolving motor, substantially as set forth.

GEORGE COLE.
